GARMENT

Isaac Firestone, Forest Hills, N. Y., assignor to
Bruck's Nurses Outfitting Co., Inc., New York,
N. Y., a corporation of New York

Application January 29, 1948, Serial No. 4,963

1 Claim. (Cl. 2—106)

1

The present invention relates to the sleeve construction of upper garments such as blouses or shirts and more particularly to the construction at the armhole portions thereof.

It is an object of the invention to provide an armhole construction for a blouse or similar garment which will permit a maximum amount of freedom or movement for the arm of the wearer without appreciable pulling or causing the garment to ride up.

A further object of the invention is to provide an armhole construction which will permit free and unrestricted movement of the arm but which, when the arm is in a position close to the body, will not cause an unsightly bulge or an uncomfortable bunching of the fabric at the armpit of the wearer.

Still another object of the invention is to provide a garment of this construction in which restriction of movement of the wearer's arm is minimized and which will have the general appearance and trimness of the usual garment in which free movement of the arm is restricted. The free movement feature may thus be incorporated into a garment without causing the garment to be noticeably different from the usual garment.

Other and further objects will become apparent upon reading the following specification together with the accompanying drawing forming a part hereof.

Referring to the drawing:

Fig. 1 shows a front view of a blouse embodying the invention.

Fig. 2 shows a plan view of a pattern for cutting the back portion of the blouse illustrated in Fig. 1. The dot and dash lines illustrate the shape of the pattern used in cutting the same portion of a conventional blouse of the same size.

Fig. 3 shows a similar pattern for cutting one of the front portions of the blouse shown in Fig. 1.

Fig. 4 shows the pattern for cutting one of the sleeve portions of the blouse.

Referring to Fig. 1, a blouse type garment designated generally as 10 is shown comprising two symmetrically shaped front portions 11 and 12 each of which is stitched to a back portion 13 by symmetrical rows of stitching 14. The three portions thus far described, when stitched together, form a sleeveless blouse type garment having two armholes therein each adapted to receive a sleeve. Sleeve portions 15 and 16 are secured in these armholes by similar circumferential rows of stitching 17 and 18 respectively. The sleeves 15 and 16 are shown provided with cuffs 19 and

20 respectively. The garment 10 is also shown provided with a collar 21 and a supplementary front portion 22 which in themselves, do not form a part of the invention. As illustrated in Fig. 1, the right sleeve 15 of the garment, which is shown in a normal or lowered position, provides a relatively small amount of surplus fabric at the underside of the armhole. It will be noted that there is no bulging or bunching of the fabric at the armpit. Referring now to the left sleeve 16 of the garment, which is shown in a raised or extended position, the shape of the armhole and the sleeve is such that a great amount of unrestricted freedom of movement of the arm is permitted without appreciable binding of the arm of the wearer or pulling of the garment.

This novel armhole construction is obtained by cutting the fabric from the patterns shown in Figs. 2, 3 and 4. In Figs. 2, 3 and 4, the solid lines represent the outline of patterns used for cutting a garment embodying the invention. The dot and dash lines illustrate the relative shape of patterns for cutting a garment of the same size but with normal or conventional construction of the armhole.

Referring to Fig. 2, it will be seen that the pattern designated generally as 23 for cutting the back of the garment is provided with curved portions 24 which form the back lower portions of the armhole are cut higher than the corresponding portions of the usual garment as indicated at 25. This arrangement provides two symmetrically disposed substantially half-crescent shaped areas 34 which extend upwardly from the dotted lines 25 to the solid lines 24. The areas 34 may therefore be considered to be added areas with respect to the usual cutting of the fabric, these added areas being bounded by the lines 24 and 25.

Similarly, the pattern designated generally as 26 which is used for cutting the two front portions of the garment has correspondingly higher cuts for the armholes at 27 than the conventional cut indicated at 28 providing the added areas 35 of generally half-crescent shape. The width of the pattern at the armhole as determined by the lateral edge 29 is also somewhat greater than the conventional width indicated at 30. In the completed garment, the lateral edges of added areas 34 of the back portion are in mutual engagement with the lateral edges of added areas 35 of the front portions.

The pattern for cutting the sleeve, designated generally as 31, provides a cut as determined by

edge 32 which is fuller than the conventional cut indicated at 33. This results in the added areas 36 which are substantially V-shaped, each arm of each V tapering away from the apex of the V. In the completed garment, one arm of each V extends lengthwise of the sleeve and the other arm of each V extends circumferentially about the lower portion of the armhole.

The resulting garment is thus provided with an armhole of greater than normal circumference and which conforms closely to the contour of the armpit of the wearer. This close conformance avoids the occurrence of an unsightly bulge or uncomfortable bunching of the fabric at the armpit. The generally half-crescent shaped extending areas 34 of the back pattern and, 35 of the front pattern, together with the two V-shaped extending areas 36 of the sleeve thus provide for cutting the fabric in a shape which will provide for a free action sleeve. This desirable feature is obtained without the use of gussets or pleats which would render the garment unsightly or uncomfortable when in normal use, yet full and unrestricted movement of the arm is permitted without pulling of the blouse upon extending the arm.

The patterns in Figs. 2, 3 and 4 are shown provided with the usual notches 37 for the location of gathers or pleats in the finished garment. The individual patterns are also shown provided with one or more holes 38 for convenience in grasping the pattern.

I have shown what I believe to be the best embodiment of my invention. I do not wish, however, to be confined to the embodiment shown, but what I desire to secure by Letters Patent is defined in the appended claim.

5 I claim:

A garment comprising a back portion and a front portion connected together to form an armhole, said front and back portions each being 10 provided with substantially half-crescent shaped inwardly extending and mutually engaging added areas in the armpit portion of the garment, and a sleeve portion connected to said armhole, said sleeve portion being provided with two V-shaped 15 added areas, each arm of the V being tapered in shape for connection to said half-crescent shaped areas, one arm of each V extending lengthwise of the sleeve and the other arm of each V extending circumferentially about the lower 20 portion of the armhole.
